UNITED STATES PATENT OFFICE

2,509,133

PAPER CUP HOLDER

Herman Carew, Easton, Pa., assignor to Dixie Cup Company, Chicago, Ill., a corporation of Delaware

Application June 23, 1944, Serial No. 541,751

4 Claims. (Cl. 65—61)

1

This invention relates to improvements in a paper cup holder, as well as to improvements in the combination of a paper cup and a holder therefor, the invention being highly desirable for use in connection with the dispensing of sodas, soft drinks, and the like in drug, confectionery, and similar stores, although the invention may have other uses and purposes as will be apparent to one skilled in the art.

The instant application is a continuation-in-part of my copending application entitled "Paper cup and holder therefor," filed March 8, 1941, Serial No. 382,300, now abandoned.

In the dispensing of sodas, malted milks, and similar soft drinks to individual customers, by means of a paper cup, usually a conical paper cup, contained within a suitable holder, it is desirable to provide some means to insure that the cup will remain in the holder during use by the customer. In the past it has sometimes happened that when a customer elevated such a cup and holder combination to the lips to drain the last portion of the contents from the cup, the cup would separate from the holder and cascade down over the wearing apparel of the customer. One of the advantages in serving soft drinks and the like in paper containers in a suitable holder is the saving of labor, in that the holder need only be washed infrequently, and the cup is disposed of after a single usage. Another highly important advantage is the sanitary character of the service. If the saving in labor is to be maintained as well as the required sanitation in service, it is essential that the cup and holder be engaged with each other in a very quick and expeditious manner, and also essential that the hands of the operator or clerk never contact the cup itself, and especially never contact the cup in the interior of the cup or in the region to which the user's lips are likely to be applied. Mechanical means requiring an operation on the part of the attendant in order to secure the cup within the holder are highly objectionable, because attendants are loathe to perform such operations and the actual performance of the operation consumes an objectionable amount of time. Accordingly, there must be automatic engagement between the cup and holder, and yet such an engagement that is sufficiently positive to prevent the accidental or unintentional dislodgment of the cup from the holder. One highly satisfactory solution to this problem has been presented and claimed in my aforesaid copending application, and the instant application is directed to another specific solution of the same problem.

2

With the foregoing in mind, it is an important object of the instant invention to provide a holder for a paper cup, and particularly a conical paper cup, the holder being so constructed as to automatically and sufficiently positively engage the cup merely upon a relatively axial movement between the cup and holder, this engagement resulting regardless of the construction of the particular paper cup and with a minimum of effort on the part of the attendant.

Another object of the invention resides in the provision of a paper cup holder having a constricted formation defining an opening near the bottom of the cup receiving cavity, which formation is relatively sharp and the opening defined thereby is of slightly less area than the corresponding portion of the cup, so that the formation tends to bite into or constrict the adjacent cup wall and positively engage the cup.

It is also an object of this invention to provide a holder for a conical paper cup, which holder embodies a tubular portion for receiving the cup apex first, and an annular knife edge portion defining an opening in the lower part of the cup receiving cavity for biting engagement with the cup wall in the apical region of the cup.

A further feature of the invention resides in the provision of a holder for a paper cup, and more particularly a conical paper cup, the holder having a cavity therein for receiving the cup apex first, and an annular knife edge formation defining an opening near the lower end of said cavity for engagement with the cup wall near the apical region of the cup, the cavity in the holder being outwardly bulged relatively to the cup both above and below the annular knife edge formation, which formation, on the contrary, is slightly less in size than the adjacent cup wall portion so that a positive indentation of the cup wall by the annular formation is effected, and the cup may retain or reassume its former size on each side of such formation.

Still a further feature of the invention resides in the provision of a holder for a paper cup having a cavity for receiving the cup apex first, there being an opening in the lower portion of that cavity defined by a relatively sharp edge of polygonal configuration so as not only to indent the wall of the cup, but also distort the wall of the cup in this region to establish a firm grip upon the cup.

It is also an object of this invention to provide a combination cup and holder wherein the cup is so made as to have an exposed edge of the paper stock on the exterior surface of the

cup, and the holder is so constructed as to embody means for biting into that exposed edge portion of the cup, regardless of the location of the edge portion and regardless of the particular structure of the cup, merely upon an axial engagement of the cup and the holder.

Still another object of the invention is the provision of a combination cup and holder wherein the holder is provided with an opening defined by a relatively sharp annular edge slightly less in size than the corresponding portion of the cup wall, and the cup is provided with a latching tab which automatically latches behind such knife edge and this, in addition to the constriction caused in the cup wall by the knife edge, provides a very simple and yet an extremely positive hold upon the cup.

While some of the more salient features, characteristics and advantages of the instant invention have been above pointed out, others will become apparent from the following disclosures, taken in conjunction with the accompanying drawings, in which:

Figure 1 is a fragmentary, part vertical sectional, part elevational view of a holder embodying principles of the instant invention showing a cup disposed in the holder;

Figure 2 is an enlarged fragmentary sectional view through the holder taken substantially as indicated by the line II--II of Figure 1, looking in the direction of the arrows, and showing the cup in elevation;

Figure 3 is an enlarged fragmentary view of similar character to Figure 2, but taken substantially as indicated by the section line III--III of Figure 2;

Figure 4 is a top plan view of the holder with the cup removed;

Figure 5 is an enlarged fragmentary vertical sectional view illustrating a slightly different construction for the holder;

Figure 6 is a fragmentary part vertical sectional, part elevational view of a holder of somewhat different structure showing the same in operative association with a cup;

Figure 7 is a top plan view of the holder of Figure 6 with the cup removed;

Figure 8 is a view of the character of Figures 2 and 3 illustrating the association of the holder of Figure 1 with a cup having a latching tab thereon; and

Figure 9 is a fragmentary plan-sectional view of the structure of Figure 8 taken substantially as indicated by the line IX--IX of Figure 8.

As shown on the drawings:

In that illustrated embodiment of the instant invention seen in Figures 1 to 4, inclusive, there is shown a cup holder 1 which is generally of hour glass shape, and which may be made of metal, a suitable plastic, or any other feasible material. The holder is preferably tubular in shape to define a cup receiving cavity therein. This cavity is provided with a wall portion 2 in its upper portion to intimately receive a conical paper cup. As illustrated, the wall portion is relatively wide in character, but it may be narrower if so desired. Below the wall portion 2 the inside wall of the holder is enlarged or widened as indicated at 3 to be definitely in excess of the size of the corresponding part of the cup.

The wider portion 3 terminates at the lower end in an annular knife edge formation 4 which defines an opening near the lower end of the cup receiving cavity. This annular knife edge for-

mation is preferably of a lesser size than the corresponding wall portion of the paper cup. That is, the knife edge formation is constricted with reference to the normal size of the paper cup. Below the knife edge formation, the inner wall portion of the holder is again enlarged beyond the size of the corresponding portion of the cup as indicated at 5, and below the enlargement 5 any suitable base formation, such as that shown 10 at 6, may be provided. If so desired, the holder 10 may be equipped with a handle 7 but such is not necessary.

In operative position within the holder is shown a conical paper cup 8 which, in the illustrated instance, is of the convolute type. Overlapping portions of the blank going to make up this cup are preferably secured together by the use of a suitable adhesive. With a cup of such formation there will be an edge 9 of the outer overlapping portion freely exposed on the outside surface of the cup. Insofar as the engagement between the cup and the holder is concerned, this particular edge portion 9 may run in any direction. A firm engagement with this edge portion will result regardless of its direction, just as long as the edge portion is in a location to be contacted by the aforesaid knife edge formation 4 when the cup enters into the holder.

In use, it is a simple expedient to stack the cups in nested relationship in a suitable container, in inverted position. The holder may then be grasped by the bottom and pressed downwardly over the uppermost cup of the inverted stack. That is all that is necessary on the part of the operator. Upon such relative axial movement between the holder and the cup, accompanied by a very slight pressure, the annular formation 4 will constrict the cup wall therearound as indicated at 10. That is, this formation will provide a definite indentation in the cup wall, and owing to the enlargement of the inner wall of the holder at 3 and 5 above, and below the knife edge formation, the cup wall may either remain or reassume its normal size above and below the indentation. Thus, there is a positive hold upon the cup by means of the holder resisting any tendency toward dislodgment of the cup from the holder. This hold is amply sufficient to prevent an accidental or unintentional dropping of the cup from the holder.

In addition to the indentation in the cup wall just above described, it will be noted, from the showing in Figure 2, that the knife edge formation will bite more positively into the exposed edge 9 of the blank of the cup. This edge protruding farther from the body of the cup than any other portion will, in most cases, be provided with a definite nick such as indicated at 11 in Figure 1 by the knife edge formation, thus materially enhancing the grip of the holder upon the cup.

If so desired, the cups may be placed in an upright dispenser, with the apices of the cups protruding below the dispenser, and the holder pressed over the lowermost cup in the stack and withdrawn from the dispenser solely by virtue of the engagement between the cup and the holder caused by the knife edge formation 4.

It will be appreciated that there is no other act necessary on the part of the operator except a simple movement of the holder over the cup in order to establish the gripping or latching engagement of the holder upon the cup.

In Figure 5 I have shown a slightly different arrangement of the knife edge formation designated 4a. In this instance, this holding edge

formation is turned downwardly somewhat so as to more forcibly resist a movement of the cup out of the holder.

It will further be appreciated from the showing in Figures 1 to 5, inclusive, that the knife edge provides something in the nature of a shoulder formation in the holder, and while this formation is referred to herein and in the appended claims as a knife edge formation, it will be appreciated that it need not be as sharp as the customary knife, but may just be relatively sharp in comparison with a shoulder formation or the equivalent lacking a definite edge.

In Figures 6 and 7 I have illustrated a holder of somewhat different construction, but one which acts in substantially the same way in connection with a cup as the holder just above described. In this instance, a holder 12 is illustrated, substantially of hour glass shape, and which may be made of any suitable material. Inside the holder there is a generally frusto-conical portion 13 which may, if so desired, be of such shape as to intimately receive a cup substantially throughout the entire length of this portion. The portion 13 terminates at its lower end in an opening defined by a polygonal formation 14 in the tubular portion. As seen best in Figure 6, this polygonal formation is inwardly turned so that an edge portion of the material abuts the inserted cup in the manner of the knife edge formation above described. In the illustrated instance the polygonal formation is shown as hexagonal, but it will be appreciated that it may have some other polygonal configuration if so desired.

Upon joining the cup and the dispenser, the polygonal edge formation 14 also causes the above described indentation 10 in the cup wall, and also nicks the exposed edge 9 of the cup stock as indicated at 11, but in addition this edge formation tends to distort the wall of the cup, i. e., cause the wall of a cup to assume a different shape in this vicinity than its normal shape. As indicated by the dotted lines in Figure 7, the cup may have a cross-sectional configuration of a circle both above and below the polygonal formation 14, but at that formation the cup must assume a shape somewhat in keeping with the formation itself. As seen in Figure 6, the portion 13 of the holder extends openly within the holder so that the entire formation functions somewhat as a shoulder, and permits an expansion or maintenance of normal shape of the cup beneath the polygonal formation. All of the advantages discussed hereinabove in connection with the showing in Figures 1 to 5 are also present with the use of the structure seen in Figures 6 and 7.

In Figures 8 and 9 I have illustrated the operation of the structure of Figures 1 to 4, inclusive, with a paper cup having a latching tab thereon. In this instance, a cup 15 is illustrated which is also a convolutedly wound conical cup but which is provided with an enlarged tab 16 in the apical region. This tab is not cemented throughout its entire area to the body portion of the cup, but is left free to project outwardly from the body of the cup by virtue of its inherent resiliency. When the cup and holder are joined, the tab flexes by the knife edge formation 4 and expands in the open area 5 beneath this formation as shown by the dotted lines in Figure 9. This feature of construction, in addition to the indentation of the cup wall as indicated at 10, provides a very positive hold upon the cup.

In all embodiments of the instant invention

hereinabove described, it will be appreciated that when it is desired to remove the cup from the holder it is a simple expedient for the attendant to grasp the upper protruding mouth portion of the cup and pull the cup from the holder, notwithstanding the fact that the cup may be damaged in so doing, because the cup is to be disposed of immediately after a single usage.

In view of the foregoing, it is apparent that I have provided a novel cup and holder arrangement wherein the cup may be positively engaged within the holder with no extra operations required on the part of an attendant, and with no need for the attendant to touch any part of the cup with his hands. The entire construction both of the holder and of the cup are extremely economical, and involve no parts to get out of order. The holder has a long life, and need only be cleansed at infrequent intervals, so that fountain service is materially expedited with the use of such holders and cups, and sanitation is maintained at an extremely high degree.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In combination, a conical paper cup having overlapping portions secured together with an edge of one of said portions on the outside wall of the cup, and a holder for said cup having a tubular portion for receiving the cup apex first, and an annular ridge extending inwardly in the lower part of said portion terminating in an annular knife edge defining an opening of slightly less size than the adjacent cup wall so as to constrict the cup wall and bite into said exposed edge of the outer overlapping portion of the cup.

2. In combination, a conical paper cup having a latching tab thereon and freely protruding tangentially from the cup body near the apex, and a holder for said cup having a tubular portion to receive the cup apex first, and an annular ridge extending inwardly from the wall of the holder and terminating in a constricted relatively sharp edge defining an opening in the lower part of said portion through which the apical part of the cup extends, said tab automatically latching behind said relatively sharp edge and said edge constricting the wall of the cup in the vicinity of said tab upon relative axial movement between the cup and holder in any relative circumferential position.

3. A tubular holder for automatically gripping an expanded conical paper cup and holding the same against accidental dislodgment, said holder comprising immovable parts providing an upper cup receiving socket and a lower base, said socket including means defining a polygonal opening in a lower part of said socket, and the sides of said polygonal opening being turned inwardly and so shaped as to provide a series of sharp edges defining an imaginary ring of less diameter than the adjacent wall portion of a cup seated in said socket.

4. A holder for a paper container having tapering side walls, said holder including a tubular portion for receiving the cup bottom end first, and an annular ridge extending radially inwardly in the lower part of said portion terminating in a relatively sharp edge defined by opposite tapers

75 on each side thereof, said edge defining an open-

ing of less size than the adjacent wall of the cup to constrict the cup wall and hold the cup in the holder against accidental dislodgement, the inside wall of said tubular portion being enlarged radially outwardly above said edge to be definitely larger than the adjacent cup wall when the cup is in the holder.

HERMAN CAREW.
